Attest,

UNITED STATES PATENT OFFICE.

WILLIAM F. ANKLAM, OF DETROIT, MICHIGAN, ASSIGNOR TO C. M. HALL LAMP COMPANY, OF DETROIT, MICHIGAN, A CORPORATION OF MICHIGAN.

LAMP.

1,089,387.

Specification of Letters Patent. Patented Mar. 10, 1914.

Application filed May 26, 1913. Serial No. 769,928.

To all whom it may concern:

Be it known that I, WILLIAM F. ANKLAM, a citizen of the United States of America, residing at Detroit, in the county of Wayne 5 and State of Michigan, have invented certain new and useful Improvements in Lamps, of which the following is a specification, reference being had therein to the accompanying drawings.

My invention relates to lamps and more particularly to lamps for vehicles.

The invention resides in the novel manner of attaching the door to the casing; in the connection between the reflector and the casing and the manner of mounting the reflector in the casing; in the means for yieldably securing the glass for the door in place, and for taking up wear between certain parts. Further in certain constructions, arrangements and combinations of parts as will more fully hereinafter appear.

In the drawings,—Figure 1 is a perspective view of a lamp embodying the invention, with the door removed; Fig. 2 is a similar view of the door looking at the inside thereof; Fig. 3 is an end elevation of the reflector; Figs. 4 and 5 are fragmentary sections respectively on the lines $x-x$ and $y-y$ of Fig. 1 with the door in place; and Fig. 6 illustrates a detail of construction.

A designates the outer casing and B the reflector arranged therein. These parts may be of any suitable type but are each herein shown of parabolic contour.

C is a bearing member forming a support for the reflector, this bearing member preferably comprising an annulus secured to the outer edge D of the casing A as by providing the bearing member with an inwardly-extending flange E which is welded to the edge D.

F is an outwardly-extending annular flange on the reflector, of a size to project over the bearing C and which is secured to the latter preferably by providing the flange F with bayonet slots G which are adapted to engage headed pins H carried by the bearing member. In order to form a tight joint between the flange F and the bearing member, suitable yielding means is interposed between such flange and the bearing. This

yielding means is herein shown as composed of a plurality of leaf springs I, three being illustrated in the drawing.

J designates the frame of the door, having 55 a flange K forming a seat for the glass L, and M designates a retaining ring for holding the glass to its seat. This ring is provided with a suitable packing as the felt annulus N, and is attached to the frame 60 through the medium of a plurality of outwardly-extending arms O which have their outer ends P adapted to engage slots Q in the frame J. The slots Q are provided with enlarged portions R which allow the outer 65 ends P to enter the more restricted portion of the slots. Thus in securing the ring M in place the ends P of the arms are registered with the cut-away portions R, then the ring is depressed so as to permit the outer 70 ends of the arms to engage the more restricted portions of the slots upon a turning of the ring M.

The engagement between the door and the casing is arranged within the casing and 75 door and preferably is such as to eliminate hinges, thereby not only simplifying the construction but forming a structure which has a more symmetrical appearance. In the specific form illustrated the door is adapted 80 to be engaged with the casing by a turning movement. As shown, S are arms preferably formed of spring metal, secured to the casing A, and having their free ends projecting through slots T in the bearing C 85 and terminating in outwardly and laterally-extending ends U, which are adapted to engage above laterally-extending lugs V upon the casing J of the door. These lugs have one end thereof provided with an in-turned portion W so as to prevent the end U from riding off the lug V after it has been engaged therewith. With such an arrangement of parts, when it is desired to engage the door with the casing, it is merely necessary to place the door upon the casing, pressing the same inward so that the lugs V will be below the plane of the laterally-extending ends U, and then rotate the door in the direction of the arrow on Fig. 1 of the drawing. After the members U and V have been engaged the portion W will prevent disen-

- gagement of the locking parts by a rotation in the direction of the arrow. When the parts U and V are properly engaged I preferably employ a locking device for automatically securing them against displacement by a rotation in the direction opposite to that of the arrow. Thus the casing J is provided with a spring X having a laterally-extending locking face Y adapted to engage a pin 10 Z upon the bearing C when the parts U and V are in proper relation. During the engagement of these parts, by relative rotation of the door and casing A, this pin will ride under the inclined surface A' of the spring 15 X and into engagement with the face Y. B' is an actuating member for the spring X and through the medium of which the latter may be actuated to move the face Y out of the path of the pin Z.
- 20 The resilient means between the bearing C and the flange F serves the further function of yieldably pressing the glass in engagement with the bearing flange K, since the ring M, when the door is engaged with the 25 casing A, seats upon an annular bearing C' on the reflector. Also the springs I retain the flanges U and V in close contact. Such an arrangement of the parts therefore, permits the resilient means between the flange 30 F and the bearing C to yieldably hold all of the locking parts in engagement, thereby not only preventing rattling between these parts, but also automatically taking up any wear which might occur, insuring tight joints at 35 all times.
- If desired the reflector—after it is engaged with the casing—may be secured against rotary movement in relation thereto as by providing a locking dog D' which is pivoted 40 to the flange F as at E' and has a shouldered outer end F' for engaging one of the locking pins H after it is positioned within its respective slot G.
- 45 Preferably the bearing C is stepped outwardly, as shown in Figs. 4 and 5. This allows the bearing C' to be properly positioned in relation to the ring M and also gives clearance for the annular member C' which is provided with the slots Q.
- 50 While I have shown and described a desirable form of my invention, I do not wish to limit my protection to the exact structure shown, but consider the invention to be of sufficient scope to cover various modifications which might be made.
- 55 What I claim as my invention is:—
1. In a lamp the combination with a casing having an inwardly-extending annular flange, of a reflector having an outwardly-extending annular flange arranged over the flange of the casing, means for securing the two annular flanges together, and a door including a transparent panel, said reflector being provided at the outer end thereof with

an annular bead arranged within and projecting beyond the outwardly-extending flange of the reflector and said bead projecting into proximity to the transparent panel. 65

2. In a lamp the combination with a casing, of a door therefor, interlocking members inclosed by the door and casing and carried respectively thereby, means for yieldably holding said interlocking members in engagement, said door including a transparent panel and a seat against which said panel is pressed by said yielding means. 70

3. In a lamp the combination with a casing, of a reflector arranged within the casing, a door for the latter, resilient means between the casing and reflector, and interlocking members upon the door and casing arranged within said casing. 75

4. In a lamp the combination with a casing provided with a flange, of a reflector arranged in and carried by the casing and having a flange extending in operative relation to the flange of the casing, and yielding means interposed between said flanges. 80

5. In a lamp the combination with a casing provided with a flange, of a reflector arranged in the casing and having a flange extending in operative relation to the flange of the casing, yielding means interposed between said flanges, and a detachable interlocking engagement between the flanges. 90

6. In a lamp the combination with a casing, of a reflector arranged in and carried by the casing, a door including a transparent panel, and a seat for said panel, said reflector being provided with a bearing portion adapted to press the transparent panel against its seat, and yielding means acting upon said reflector. 100

7. In a lamp the combination with a casing, of a reflector arranged therein, a door for the casing, means for yieldably pressing the reflector toward the door, the latter including a transparent panel, and a packing member interposed between the reflector and the panel. 110

8. A door for a lamp, comprising a casing having a seat, a transparent panel engaging said seat, a member for securing said panel to its seat, and detachable interlocking members upon said member and the casing adapted to be engaged by a relative rotary movement thereof. 115

9. A door for a lamp, comprising a casing having a seat, a transparent panel engaging the seat, a ring for securing the panel to its seat, a resilient packing carried by said ring, and lugs upon the latter, there being slots in the casing with which said lugs have a detachable interlocking engagement. 120

10. A door for a lamp, comprising a casing having a seat, a transparent panel engaging said seat, a ring for securing the panel to its seat, and arms upon the ring, 125

there being slots in the casing with which said arms have a detachable interlocking engagement.

11. In a lamp the combination with a casing, of a door, a reflector arranged in the casing, inter-engaging members upon the casing and reflector, means acting to yieldably press the reflector toward the door, the latter including a transparent panel and compressible material interposed between the reflector and the door.

12. In a lamp the combination with a casing, of a door, a reflector arranged in the casing and carried thereby, said reflector being adapted to move longitudinally of the casing, and means interposed between the reflector and casing for yieldably pressing the reflector toward the door, the latter including a transparent panel and a compressible material interposed between the reflector and the door.

13. In a lamp the combination with a casing provided with a flange, of a reflector arranged in and carried by the casing and movable longitudinally thereof, means for yieldably pressing the reflector outward, and means for limiting the outward movement of the reflector.

14. In a lamp the combination with a casing provided with a flange, of a reflector arranged in the casing and having a flange extending in operative relation to the flange of the casing, yielding means acting to press the reflector outward, and means carried by one of said flanges engaging the other flange for limiting the outward movement of the reflector.

15. In a lamp the combination with a casing provided with a flange, of a reflector arranged in the casing and having a flange extending in operative relation to the flange

of the casing, a headed member carried by one of said flanges, the other of said flanges being provided with a bayonet slot for engaging the headed member, and yielding means interposed between said flanges.

16. In a lamp the combination with a casing, of a reflector arranged therein and carried thereby, yielding means interposed between the casing and reflector, a door including a transparent panel and a seat against which said panel is pressed by said yielding means, and interlocking members in the door and casing held in engagement by said yielding means.

17. In a lamp the combination with a casing provided with a flange, of a reflector arranged in the casing and having a flange extending in operative relation to the flange of the casing, a plurality of spaced headed members carried by one of said flanges, the other of said flanges being provided with bayonet slots for engaging the headed members, and yielding means interposed between said flanges.

18. In a lamp the combination with a casing provided with a flange, of a reflector arranged in the casing and having a flange extending in operative relation to the flange of the casing, a plurality of spaced headed members carried by one of said flanges, the other of said flanges being provided with bayonet slots for engaging the headed members, yielding means interposed between said flanges, and means for preventing relative rotation between the casing and reflector.

In testimony whereof I affix my signature in presence of two witnesses.

WILLIAM F. ANKLAM.
